RECEPTACLE CLOSURE

Augustus L. Merolle, Brooklyn, N. Y.

Application November 22, 1933, Serial No. 699,183

14 Claims. (Cl. 215—95)

This invention relates to a receptacle closure and particularly to a closure which when once unsealed can not be again restored to its original condition but which will include a part adapted 5 to serve thereafter as a temporary sealing element.

An object of the invention is to provide a closure of the type indicated which will include two separate elements one being a closure element proper and the other being a sealing or retaining element for the closure element, the sealing element being removable in its entirety and being not returnable but the closure element being of a character adapted for repeated use.

15 A further object is to provide a sealing or retaining element so constructed as to be easily removable and incapable of re-use without detection of the fact of its removal.

A further object is to provide a retaining element in the form of a strip of sheet metal bent around the receptacle and the closure element and having its opposite ends interlocked by parts easily separable but adapted to become broken or otherwise deformed so as not to be returnable 25 to their original condition.

A further and more detailed object is to provide a retaining band as indicated having its opposite ends interfolded and so constructed as to be easily unfolded to permit removal of the band 30 and being at the same time incapable of return to original interfolded condition.

A further object is to provide inter-folded ends formed with one or more lines of weakness thereacross positioned to insure fracture of the 35 material of the band whenever the inter-folded parts are unfolded and refolded.

A further detailed object is to so arrange the inter-folded end portions as to provide for the easy access of a tool wherewith to effect unfolding.

A further object is to so construct the band that it will be likely to buckle when its ends are spread apart sufficiently to permit removal of the band, thereby providing visual indication of 45 the fact of removal.

A further object is to so construct the receptacle as to facilitate the retention of the closure element and also to facilitate the formation and the easy removal of the band element.

50 Other objects and aims of the invention, more or less specific than those referred to above, will be in part obvious and in part pointed out in the course of the following description of the elements, combinations, arrangements of parts and 55 applications of principles constituting the in-

vention; and the scope of protection contemplated will be indicated in the appended claims.

In the accompanying drawings which are to be taken as a part of this specification, and in which I have shown merely a preferred form of 5 embodiment of the invention:—

Fig. 1 is a side elevational view of a receptacle closure constructed in accordance with this invention and showing the same as it appears in position upon a receptacle constructed to receive it, a portion of said figure being broken away and shown in vertical section.

Fig. 2 is an enlarged horizontal fragmentary sectional view substantially upon the plane of line II—II of Fig. 1.

Fig. 3 is an enlarged horizontal fragmentary sectional view substantially upon the plane of line III—III of Fig. 1.

Fig. 4 is a plan view of opposite end portions of the blank from which the band appearing in 20 Figs. 1 to 3 is formed.

Fig. 5 is a view similar to Fig. 1 but illustrating a modified construction of the retaining band.

Fig. 6 is an enlarged horizontal fragmentary sectional view substantially upon the plane of line VI—VI of Fig. 5, and

Fig. 7 is a plan view of opposite end portions of the blank from which the band appearing in 25 Figs. 5 and 6 is formed.

Referring to the drawings for describing in detail the structures illustrated therein, and referring first to the structure Figs. 1 to 4, the reference character L indicates the closure element while the reference character G indicates the retaining element or band.

The receptacle is indicated generally by the reference character H.

The closure element L may be of any type but as here shown is an ordinary sheet metal screw cap having a top wall portion 1 and a pendant 40 annular flange portion 2 threaded to interengage with the threads 3 provided upon the receptacle.

At the lower edge of the flange portion the closure or cap L is formed with an annular outstanding wire edge 4.

45 A sealing gasket as 5 may be provided within the cap for overlying the upper annular edge of the receptacle if desired.

The closure element or cap L is thus seen to be 50 adaptable for use as a closure for the receptacle independently of whether or not the retaining band G is present, and once the retaining band has been removed said cap may be utilized indefinitely.

The purpose of the retaining band is to initially 55

hold the cap L against unintentional displacement and to indicate by its absence, or by the mutilation or deformation of some part of itself, the fact that the cap L may have been removed.

5 The removal of the band or the deformation of some part thereof will thus serve as notice to the purchaser of the receptacle that the receptacle contents may have been tampered with.

The retaining band G may be formed of a 10 single strip of sheet metal of suitable length to entirely surround the wire edge portion 4 of the cap L, as indicated. Its opposite end portions 6 and 7 are formed with return bends or flaps 8 and 9 which are inter-folded with each other as 15 most clearly indicated in Fig. 2 so that said opposite ends are joined together to hold the band in its proper normal position surrounding the receptacle.

The upper annular edge portion of the band is 20 turned inwardly so as to provide an inturned annular flange 10 to engage over the upper surface portion of the wire edge 4, and after the band has been properly placed then its lower annular edge portion is turned inwardly to form an inturned 25 annular flange as 11 to engage the under surface portion of an annular rib part 12 provided upon the receptacle.

In order to permit of easy removal of the retaining band the relatively under end portion 7 30 of the band is formed with a slot as 13 so that the flap 9 includes two parts as 14 and 15 spaced away from each other across the intervening slot 13, and said slot is of a length so that a portion thereof is exposed as an opening beyond the end 35 of the seam as clearly indicated in Fig. 1 so as to facilitate the easy introduction of a suitable tool A, as for instance a fork tang, to position beneath the intermediate part of the opposite end 6 of the band, the tool being thus in ideal position to 40 lift or wedge the seamed portions outwardly and apart.

The parts 14 and 15 of the end 7 inter-fold with the upper and lower end portions of the flap 8 of end 6, and these inter-folded parts are bent 45 or folded tightly together, as clearly indicated in Fig. 2, but preferably the intermediate portion of the flap 8, which overlies the slot 13, is less sharply bent and thereby provides a more rounded bend, as indicated at 16 adjacent to the tool 50 admitting opening at the end of slot 13, thereby making said opening more prominent and clearly defined and at the same time providing a suitable guide surface to assist in guiding the tool into the opening.

55 As a means of insuring against successful return of the inter-folded portions to interlocked engagement after having once been separated it is proposed that said inter-folded portions be so weakened that while they will be sufficiently 60 strong to serve their intended purpose of holding the ends of the band normally connected yet they will fail if attempt be made to unbend and rebend them. To this effect the drawings suggest that a line of weakness as 17 may be formed 65 across the hinge region of the parts 14 and 15 and that a similar line of weakness as 18 may be formed across the end portion 6 of the band in close proximity to the line 17, as seen in Fig. 2, so that any unbending movement of the inter-folded parts will occur sharply along these lines 70 of weakness and produce fracture of some part or all thereof.

It is proposed further that after the band has been positioned upon the receptacle and preferably, though not necessarily, at the time of turn-

ing in the under flange 11, the central annular part of the band, including the interfolded or seam parts, shall be formed into an inwardly bent portion as 19. The rib 12 of the receptacle may be provided with an annular channel as 20 5 to receive the portion 19, and incidentally to form annular abutment shoulder portions 21 and 22 against which the band may be pressed in forming the portion 19.

The portion 19 is more shallow than the channel 10 20 so that an annular opening as 23 is provided beneath the portion 19 into which the fork tang, or other tool introduced for prying apart the seam, may be accommodated regardless of the circumferential position of the seam on the 15 receptacle.

Due to the semi-circular cross sectional contour of the portion 19 said portion constitutes an 20 annular stiffening rib upon the band which, together with the stiffness provided by the flanges 10 and 11, provides a suitable degree of resistance against such separation of the end portions of the band as is necessary to remove the band from the receptacle. Because of this resistance it follows that any effort to separate the inter-folded seam parts will almost of necessity result 25 in a sharp bend of the end portion 6 along the line of weakness 18. Also it is noted that any bending along the line of weakness 18 will, on account of the semi-circular cross section of the portion 19 across which said line of weakness extends, cause either a straightening out of the semi-circular contour of the portion 19 in the region of the line of weakness, or a positive fracture 30 of the material along said line. The hinge action must occur along a single straight line and the parts must therefore either move into this straight line or separate from each other along regions lying to one side of said straight line. And hence it will be substantially impossible 35 to bend the end 6 along the line 18 without such a fracture or deformation of the material as will be conspicuously noticeable.

Also, the spreading apart of the ends of the band against the resistance generated by the 45 portions 10—11 and 19 will so stretch or buckle one or more of said portions as to indicate the fact of the spreading.

In the modification Figs. 5 to 7 the structure is the same as has already been described, except 50 that in this instance the end portion 6 of the band is formed with two endwise slots 24 and 25 thereby providing a central tongue 26 constituting a finger grip extension of the central portion 19 of the band. Throughout the remainder 55 of its circumference the band is formed with parallel lines of weakness as 27 and 28 bordering the central portion 19 so that a user, by gripping the portion 26, may readily tear out the entire circumferential length of the portion 19 leaving the 60 upper and lower marginal portions as 29 and 30 of the band separated, and thus permitting the easy removal of the closure element.

The upper portion 29 may be lifted away without hindrance, and discarded. 65

The lower portion 30 may be easily removed by unbending its seamed end portions which are now of such small dimensions that unbending can be easily performed by one's fingers.

The transverse line of weakness 17 in the end portion 7 of the band may be present as in the previous structure, and the transverse line of weakness 18 may likewise be present as before except that its midportion, where it traverses 70 75

the portion 19, may be omitted, as indicated in Fig. 7.

When an operator pulls outwardly upon the tongue 26 the force thus applied may unbend 5 the inter-folded end portions of the band, substantially as in the structure Figs. 1 to 4, but if the inter-folded portions successfully resist bending at this time then the pull upon the tongue 26 will result in tearing out the entire portion 10 19, after which the upper and lower portions 29 and 30 of the band may be removed as above suggested.

While the drawings indicate that the portion 19 may in this instance be of semi-circular cross 15 section, it will be apparent that said portion may be formed in the same plane as the upper and lower portions 29 and 30. The semi-circular formation however is preferable since it not only lends strength to the portion 19 and facilitates 20 its more accurate severance along the lines of weakness 27 and 28 but it also insures that any outward lifting of the tongue 26 will of necessity cause such a buckling or wrinkling of the metal 25 as will indicate to an observer the fact that the seal has been tampered with.

A closure device constructed as herein shown and described is of easy manufacture and of practical and efficient form in use. The retaining band serves to hold the closure element against 30 possibility of accidental loosening, but when the ends of the band are separated, or the portion 19 torn out, the band may be readily detached from the receptacle and disposed of as of no further use, leaving the closure or cap L as an attractive and efficient temporary closure for the 35 receptacle, and any tampering with the band such as would permit the removal of the closure or cap L will of necessity result in such mutilation, deformation or fracture of some part of the 40 band as will indicate to an observer the fact that the contents of the receptacle have probably been meddled with.

As many changes could be made in this construction without departing from the scope of 45 the invention as defined in the following claims, it is intended that all matter contained in the above description, or shown in the accompanying drawings, shall be interpreted as illustrative only and not in a limiting sense.

50 Having thus described my invention, what I claim as new and desire to secure by Letters Patent is:—

1. A receptacle closure comprising a cap member and a separately formed retaining band removable to permit removal of the cap, and the band having opposite circumferential end portions interfolded with each other to hold the ends 55 band having opposite circumferential end portions being folded back upon itself, at least one 60 of the interfolded end portions having a line of weakness formed thereacross of a character permitting unfolding of said end portions but rendering said portions incapable of refolding without fracture along said line of weakness.

65 2. A receptacle closure comprising a cap member and a separately formed retaining band removable to permit removal of the cap, and the band having opposite circumferential end portions each folded back upon itself as a bendable 70 hook said hooks being engaged together as an interfolded seam holding the ends of the band connected but separable by unbending of said hooks, and a finger grip tongue connected to simultaneously unbend both of said hooks.

75 3. In combination, a receptacle and a closure

therefor, the closure comprising a cap member and a separately formed retaining band removable to permit removal of the cap, the band having opposite circumferential end portions interfolded with each other and there being an opening provided through the material of the band adjacent to said inter-folded end portions through which to insert a tool for unbending said inter-folded end portions, and said receptacle having a surface depression providing a hollow 10 space beneath said band and said interfolded end portions adapted to accommodate the inner end portion of said tool.

4. In combination, a receptacle and a closure 15 therefor, the closure comprising a cap member and a separately formed retaining band removable to permit removal of the cap, the band having opposite circumferential end portions interfolded with each other and there being an opening provided through the material of the band 20 adjacent to said inter-folded end portions through which to insert a tool for unbending said inter-folded end portions, and said receptacle having an annular groove therein providing a hollow space beneath the band extending entirely 25 around the receptacle so as to accommodate the inner end portion of the tool inserted through said opening irrespective of the radial position of said opening with respect to the receptacle.

5. A receptacle closure comprising a cap member and a separately formed retaining band removable to permit removal of the cap, the band having opposite circumferential end portions inter-folded with each other to hold the ends separately connected together, the band also having a pair of lines of weakness extending circumferentially thereof spaced apart demarking an annular tear-out strip intermediate the top and bottom margins of the band, and said tear-out 40 strip having an extending portion constituting a starting tongue disposed directly adjacent to said inter-folded end portions so as to apply an unfolding strain upon said end portions by said tongue.

45 6. A receptacle closure comprising a cap member and a separately formed retaining band connected therewith having its bottom marginal part adapted for connection with the receptacle, said band having a pair of lines of weakness extending circumferentially thereof spaced apart demarking an annular tear-out strip intermediate the top and bottom margins of the band, and said tear-out strip having an extending portion constituting a starting tongue extending from one 50 end thereof.

65 7. A receptacle closure comprising a cap member and a separately formed retaining band removable to permit removal of the cap, and the band having opposite circumferential end portions interfolded with each other, one of said interfolded end portions including a bendable folded back part constituting a hook extending substantially entirely across the band, the other of said interfolded end portions including a pair of bendable folded back parts constituting two hooks spaced away from each other one adjacent to the upper margin of the band and the other adjacent the lower margin of the band, said two hooks of the second end portion interengaging with the 70 single hook of the first end portion at points spaced adjacent to opposite ends of the hook of the first end portion and leaving the mid-region of the hook of said first end portion free of the hooks of the second end portion and ac- 75

cessible to a tool for unbending the hook portions.

8. A receptacle closure comprising a cap member and a separately formed retaining band removable to permit removal of the cap, and the band having opposite circumferential end portions separably connected together, the separable connection consisting of turned back hook portions of the opposite ends of said band hooked together and adapted for release by unbending of said hook portions, and the hook portion of one end of the band consisting of hook parts spaced away from each other and engaging the hook portion of the other end at spaced points in the length of the second hook portion transversely of the band and leaving the mid region of the second hook portion free of the first hook portion and thereby accessible to a tool to unbend the hook portions.

9. A receptacle closure comprising a cap member and a separately formed retaining band connected therewith having its bottom marginal part adapted for connection with the receptacle, said band having a pair of lines of weakness extending circumferentially thereof spaced apart defining an annular tear-out strip intermediate the top and bottom margins of the band, and said tear-out strip being semi-circularly concaved in cross section the cross sectional curvature extending to and terminating in said lines of weakness.

10. In combination, a container having a neck defining a filling and discharging opening, a closure for the opening, a seal for securing the closure against movement, said seal comprising an elongated metal band encircling the neck and closure, a vertical seam connecting the ends of the band, and a finger piece formed integral with the band and providing means for opening the seam and removing the band.

40 11. In combination, a container having a neck defining a filling and discharging opening, a closure for the opening, a seal for securing the closure against movement, said seal comprising an elongated metal band encircling the neck and

closure, a vertical seam connecting the ends of the band, and a finger piece constituting a reduced longitudinal extension at one end of the band providing means for opening the seam and removing the band.

5 12. In combination, a container having a neck defining a filling and discharging opening and an annular downwardly facing shoulder encircling the neck, a closure for the opening, a seal for securing the closure against movement, said seal comprising an elongated metal band encircling the neck and closure, and having an area intermediate its upper and lower ends contracted to take over said shoulder, a vertical seam connecting the ends of the band, and a finger piece formed integral with the band and providing means for opening the seam and removing said band.

10 13. In combination, a container having a neck defining a filling and discharging opening, a closure for the opening, a retaining band for securing the closure against movement lengthwise of the neck, said band comprising an elongated metal strip encircling the neck and closure, a vertical seam connecting the ends of the band and including interlocking hooks formed by folding the end portions of the strip upon themselves, and a finger piece providing means for opening the seam and removing the band.

15 14. In combination, a container having a neck defining a filling and discharging opening, a closure for the opening, a retaining band for securing the closure against movement lengthwise of the neck, said band comprising an elongated metal strip encircling the neck and closure, a vertical seam connecting the ends of the band and including interlocking hooks formed by folding the end portions of the strip upon themselves, and a finger piece providing means for opening the seam and removing the band, said finger 20 piece constituting a reduced longitudinal extension formed integral with and at one end of said band.

25 AUGUSTUS L. MEROLLE.
